R. W. LIVINGSTON,
SUPPORT FOR ELECTRIC FLASH LAMP CASES,
APPLICATION FILED JAN. 13, 1920.

1,363,664.

Patented Dec. 28, 1920.

FIG. 1.

FIG. 2.

FIG. 5.

FIG. 3.

FIG. 6.

FIG. 4.

INVENTOR

RAYMOND W. LIVINGSTON

By Joseph J. O'Brien

ATTORNEY

UNITED STATES PATENT OFFICE.

RAYMOND W. LIVINGSTON, OF SPRINGFIELD, MASSACHUSETTS.

SUPPORT FOR ELECTRIC FLASH-LAMP CASES.

1,363,664.

Specification of Letters Patent. Patented Dec. 28, 1920.

Application filed January 13, 1920. Serial No. 351,247.

To all whom it may concern:

Be it known that I, RAYMOND W. LIVINGSTON, a citizen of the United States of America, and resident of Springfield, in the county of Hampden and State of Massachusetts, have invented certain new and useful Improvements in Supports for Electric Flash-Lamp Cases, of which the following is a full, clear, and exact description.

10 This invention relates to improvements in supports for electric flashlamp cases and the leading object of the invention is to provide an adjustable support adapted to fold neatly against the side of the lamp case which will 15 when extended support the lamp case in any desired angle so that the light may be projected against any particular object or place for a desired period without being held by the hand.

20 Another object of the invention is the provision of an adjustable electric flashlamp support which can be adjusted longitudinally of the case and detachably connected to any lamp case and which can be angularly 25 adjusted relative to the case to support the same in any desired angular position.

Another object of the invention is the provision of a flashlamp support consisting of 30 two pieces, one a clamp adapted to detachably embrace a lamp case and the other a wire leg having pivotal connection at its ends with the clamp and provided with an offset terminal portion adapted to have a spring clutching action with the case, the 35 clamp being formed with offset portions adapted to be engaged by the side members of the leg whereby the leg will be maintained in any desired angular relation with the clamp and the case.

40 Another object of the invention is to provide a clamp for this purpose which will have a positive clutching action on the case to which it is connected.

With the above and other objects in view 45 this invention relates to certain new and useful constructions, combinations and arrangements of parts, clearly described in the following specification and fully illustrated in the accompanying drawings, in which:

50 Figure 1 is a side elevation showing the device attached to a lamp case such as commonly used to contain the lamp, lens and battery of flash devices, the lamp case being supported so as to project the light rays at 55 an upward angle of about 45 degrees.

Fig. 2 is a side elevation showing the support folded against the side of a lamp case.

Fig. 3 is an end view of the lamp.

Fig. 4 is an end view of the yoke of the leg rest.

Fig. 5 is a detail of the connection between the leg member and the clamp.

Fig. 6 is a vertical section of the clamp.

Referring to the accompanying drawings 5 designates a tubular case adapted to contain a battery and 6 the lens thereof, through which the light rays are projected from a lamp bulb energized by the battery contained in the case as in the common constructions.

As shown my device consists of a clamp 7 and a leg rest or supporting member 8; the clamp 7 is formed of spring metal and is of U shaped formation so that it may be slipped on the body of the case 5 by a lateral movement, 75 the clamp 7 being formed with opposing jaws 9 and 10 adapted to grip the sides of the case. The body of the clamp is formed with corrugations or beads 11 adapted to reinforce the same so the deformation of the 80 clamp will be resisted by the metal of which it is composed more effectively.

Each jaw of the clamp is formed with a terminal opening 12 adapted to receive the end portion 13 which is offset on the side arm 85 14 of the leg rest member. The metal surrounding the opening 12 is outwardly offset to form a circular raised portion 15, whereby the offset portion 13 may swing in an arc 90 against the inner side of the jaw without scraping the case.

Each jaw is also provided with a transverse corrugated portion 16 providing a relatively shallow spring loop adapted to be axially alined with the lamp case when the 95 clamp is attached thereto and which is designed to maintain the terminal portions of the jaws under gripping tension on the lamp case and also to provide a bearing surface for the side arms 14. The offset portion 16 100 is formed with a series of offset or outwardly disposed semi-spherical abutments or stops 17 adapted to be engaged by the side arms 14 as these side arms swing on the jaws as indicated in Fig. 1.

The leg member 8 is formed with a transverse U shaped yoke 18 which connects the arms 14 to each other and which is adapted to have a spring clutching action with the side of the case 5 by a lateral 110

movement as in the case of the clamp 7. The yoke 18 is formed so that the terminal portions 18^a are deflected inwardly relative to the body of the yoke so as to have a snap fit on the case, whereby the yoke will be retained on the case by the spring pressure exerted by the jaws 18^a against the rounded surface of the case as indicated in Fig. 4 in dotted lines, the jaws being shown in normally deflected positions in full lines.

The clamp 7 is adapted to slide longitudinally on the case 5 and to be detached therefrom at any point of its engagement with the case and to maintain a spring gripping action on the case which will permit the arms 14 of the leg member 8 to swing against a spring bearing surface 16. The arms 14 are adapted to swing on the spring bearing surface 16 so as to snap over them outwardly of said abutments 17 whereby the arms 14 will be maintained by a friction and spring tension against the particular abutments with which the arms are adjusted as indicated in Fig. 1.

25 In the position shown in Fig. 1 the arms 14 are in abutting relation against the central stops 17 but should it be desired to support the case 5 at an angle less than 45 degrees the arms may be adjusted with one of 30 the upper stops and the clamp shifted relative to the case to secure the desired adjustment. Should it be desired to adjust the arms of the clamp to support the case at a higher angle the arms may be brought 35 in abutting relation with any of the lower stops. When the leg rest is connected to the case the jaw portions 18^a will engage the floor or support on which the entire device is disposed.

40 The lamp case may also be supported by suspending the yoke 18 upon a hook or any other device and similar adjustments may be attained when thus suspended.

45 My device does not require any alteration of the case construction of flashlamps and is easily attached and detached and readily adjusted to any desired position. When attached to a battery case the clamp and the supporting leg member will lie neatly 50 against the side of the case and in no way interfere with the free use of the device by the hand of the user while the leg member is in folded position, as the clamp and the leg member will be retained in their folded 55 positions as shown in Fig. 2 by spring tension exerted by the jaws of the clamp and the jaws of the yoke.

Having described my invention I claim:

60 1. An adjustable support for lamp cases consisting of a yoke of U shaped formation

and provided with jaws formed with spaced stops extending transversely thereof, and a leg member having arms pivotally directly connected to said jaws to swing successively against the stops to support the case in various angular positions.

2. An adjustable support for lamp cases consisting of a U shaped spring case clasping member having jaws formed with transversely disposed offset portions providing spring loops, said loops being formed with spaced stops, and a leg member having companion arms pivoted directly to said jaws to swing against the loop portions and stops and provided with a yoke connecting said arms and adapted to have a spring clasping action on the case.

3. A flashlamp support consisting of a U shaped member adapted to clasp the body 80 of a flashlamp case and providing opposing jaws, one of said jaws having a series of space stops extending along the lamp case in longitudinal relation thereto, and a leg member having terminals directly pivoted to said jaws whereby said leg member will swing in an arc against said stops and be frictionally retained in place.

4. A support for flashlamp cases consisting of a U shaped clamp adapted to clasp a flashlamp case and provide opposing jaws on either side of the case, said jaws being provided with bosses having openings therein and outwardly offset from said jaws, one of said jaws being provided with a series 95 of outwardly offset stops extending transversely of the jaw, and a leg member consisting of side portions adapted to swing successively against the stops and terminal portions pivoted in the openings of said bosses, said side members being provided with a connecting loop portion adapted to snugly fit in the folded position against the side of the lamp case.

5. A support for flashlamps consisting of a U shaped clamp adapted to grip the body of a flashlamp case and provide a jaw on each side of the case, each of said jaws being provided with outwardly offset portions and one of said jaws being provided with a series of stops extending transversely thereof, a leg member comprising side members having terminal portions directly pivoted to the outwardly offset portions of said jaws and adapted to yieldingly engage said stops, and means connecting said side members to each other.

Signed by me at Springfield, Massachusetts.

RAYMOND W. LIVINGSTON.
